UNITED STATES PATENT OFFICE.

LOUIS J. CRECELIUS, OF ST. LOUIS, MISSOURI, ASSIGNOR OF ONE-HALF TO
ANDREW WARREN, OF SAME PLACE.

LIFTING-JACK.

SPECIFICATION forming part of Letters Patent No. 391,691, dated October 23, 1888.

Application filed April 10, 1888. Serial No. 270,218. (No model.)

To all whom it may concern:

Be it known that I, LOUIS J. CRECELIUS, of St. Louis, in the State of Missouri, have invented a new and useful Improvement in Lifting-Jacks; and I do hereby declare that the following is a full, clear, and exact description of the same.

The invention hereinafter set forth is an improvement upon the lifting-jack described in certain applications heretofore filed by me in the Patent Office of the United States and numbered, respectively, 256,133 and 256,134.

The invention relates more particularly to the gripping mechanism by means of which the lifting-bar is raised or held or lowered; and it is designed and specially fitted for the tapered form of lifting-bar shown in said applications, but is not necessarily limited to that form of lifting-bar.

In the accompanying drawings, in which my said invention is illustrated, Figure 1 represents a central vertical section of the jack with my improved grip, the section being taken across the gripping mechanism. Fig. 2 shows the jack in cross-section on line xx of Fig. 1. Fig. 3 is a detail view of a modification.

The standard A of the jack is of ordinary construction, having a vertical channel for the lifting-bar a . This bar has a lifting-foot, b , and is made tapering from the upper end downward. The taper may be a plain taper on an entire side, or it may be formed in a groove such as that shown at c in dotted lines at Fig. 2. In the standard is shown a chamber, d , on one side, which may be duplicated on the other side, if desired. On the inner side it opens into the channel, and, as shown, it is also open on the other side; but it may be closed on the outside and open on the top instead, the opening being formed in any way convenient for casting.

The gripping device consists of a wedge, e , the inner face of which bears directly against the face of the lifting-bar, as shown in Fig. 1, and preferably the face of the wedge which bears against the bar is made slightly curved outwardly to allow it to conform to the surface of the bar under all circumstances and in whatever position the tapered bar may happen to

be at the time of gripping. The outside face 50 of the wedge bears against a bolt or pin, f , inserted transversely through the walls of the chamber. This face is also preferably slightly curved inwardly, to correspond to the form of the face which bears upon the bar. The difference between the thickness of the upper and lower ends of the wedge should exceed that between the upper and lower ends of the bar, so that as the bar is lifted to bring the lower or thinner end opposite the wedge the 60 latter shall not fall below the bolt, and the thinner end of the wedge should be of sufficient thickness to give the proper grip upon the upper part of the bar. The bar is shown in its lowest or normal position in full lines, Fig. 65 1, and the position of the wedge e is also shown in full lines, the lower or thinner parts of the wedge bearing at this time upon the bar. As the bar is lifted, the taper form increases the space between the bearing-surface 70 and the bolt f and the wedge drops down into this space, and when the bar is up and the space is largest the larger part of the wedge will be in place between the bearing-surface of the tapered bar and the bolt, as shown in 75 dotted lines at e^2 , Fig. 1.

The bolt f may be in fixed position for jacks of that class which are used for lighter work or where no lowering is required; but for other kinds of work I have provided, also, in this form of grip a lowering device. For this purpose I slot the walls of the chamber d , as shown in Fig. 3, the slot being inclined, as shown, to align the bearing-face with the center of the pivot and the bolt, and I place the bolt or pin 85 f^2 within this slot. Outside of the pin or bolt when in this slot and lying across the face of the wedge I place an eccentric lever, H . Its pivot is in line parallel with the bolt and its eccentric head h bears against the bolt 90 and holds it to the wedge e^2 . The amount of eccentricity of the head corresponds to the taper of the lifting-bar, and, obviously, as the lever is turned to bring the lower face of the eccentric head against the bolt, the wedge will 95 be allowed to retract. Supposing the bar to be raised with a load which the operator desires to lower, the wedge is then down, and as

the bolt and wedge are permitted to retreat from the face of the bar it may slip down, being held at any point by the eccentric. The operator, holding the eccentric lever, may thus control the load and lower it to any point and there hold it. This adjustable holding-lever H is substantially the same as that shown in connection with a movable rear wall in one of my aforesaid applications, No. 383,710, and 10 represents here any suitable form of adjustable holder for the pin. When this holding-lever is not used, the bolt-pin is fixed, and may be, in fact, a part of the casting itself; but I prefer to use a bolt or pin, as it may then be made 15 of hardened steel and may be removed when worn. The wedge also is made of hardened metal.

10 15 A similar wedge, e' , and pin f' , as above described, are also shown in the lifting-head E ; 20 but in this head the pin is fixed, or a fixed bearing for the wedge, or substantially the same form, is made as a part of the head casting itself. A lifting-pin, h , is provided, fixed on the standard and operating to lift the wedge 25 or release it when the head is down by entering a hole in the bottom of the head and striking the under part of the wedge. This permits the lowering, and is described also in connection with a roller in my said application. The amount of taper of the bar and the 30 wedge may be varied; but they must correspond in amount to each other, as heretofore explained.

35 The faces of the wedge are slightly curved, and always give a better bearing-surface on the bar, the taper of which supplements that of the wedge and renders the grip secure under all circumstances, and it is not impaired by the action of dirt or grease upon the bearing surfaces.

40 The precise form of the bolt is not material, as it may be flat or of other forms of cross-section than that shown.

For operating the lifting-head, a lifting-lever, 45 A' , is employed. (Shown in dotted lines.) This lever is provided with a socket portion, a' , and two short arms, a' , only one of which is shown in dotted lines. These arms pass to either side of the lifting-head, and are connected 50 with links a' , one of which is shown in dotted lines, which are connected in turn to the lifting-head. The depression of the lever raises the head, and with it the bar, the grip in the head operating on the depression of the lever. When the head is lowered, the grip in the 55 standard operates to hold the bar in the position to which it has been raised. When the head is to be lowered, the lever is raised to

50 55 60 65 70 75 80 85 90 95 100 105 110

lower the head until the pin in the standard raises the wedge in the head, and then the operator may lower gradually the load by manipulating the holding-lever. A spring-pin, as q or q' , may be provided to bear on the wedge; but this is not needed except when the jack is worked in horizontal position. 60 65

When the holder is not used on the wedge in the standard, a lifting device, as shown at M , must be used in connection with the lower wedge for the purpose of lowering the bar or its load. This device consists of the slide m and a lever, m' , to move the same. The chambers, obviously, require no fitting, and the wearing parts are all removable. 70

I claim—

1. In combination with the lifting-bar and 75 lifting-lever of a jack and its standard, the bolt and the wedge arranged between the bolt and the face of the lifting-bar, substantially as described.

2. In combination with the lifting-bar and 80 lifting-lever of a jack and its standard, the bolt and the wedge arranged between said bolt and the face of the lifting-bar, said wedge having its faces curved, substantially as described.

3. In combination, the standard of a jack, a 85 lifting-bar having a tapered face, a lifting-lever, the bolt, and the wedge arranged between said bolt and the tapered face of the lifting-bar, substantially as described.

4. A lifting-jack comprising the following 90 elements: a standard, a lifting-lever, a lifting-bar, a wedge arranged in contact with the face of said bar, and an adjustable holder for keeping said wedge in contact with the face of the bar, or to lessen its contact therewith, sub- 95 stantially as described.

5. In combination with the lifting-bar and lifting-lever of a jack and its standard, a bolt, a wedge arranged between said bolt and the face of the lifting-bar, and an adjustable holder, 100 H , for said bolt, substantially as described.

6. In combination with the lifting-bar and lifting-lever of a jack and its chambered standard, a supporting-bolt and a wedge, e , arranged between said bolt and the face of the lifting-bar, the rear face of the wedge having a contour corresponding to the face of the bolt, substantially as described. 105

In testimony whereof I have signed my name to this specification in the presence of two subscribing witnesses. 110
